UNITED STATES PATENT OFFICE

FRANK MOSSBERG, OF ATTLEBORO, MASSACHUSETTS

COP HOLDER

Application filed January 9, 1930. Serial No. 419,551.

My present invention relates to cop holders for braiding machines and the like; one object of my invention is to provide an improved locking structure for the ratchet head and the central tube of the cop holder.

Another object is to provide a locking structure which will prevent relative turning of the parts.

A further object is to provide an improved outer sleeve construction having great resiliency and holding power.

With these and other objects and advantageous features in view, the invention consists of novel arrangements of parts more fully disclosed in the detailed description following, in conjunction with the accompanying drawings, and more particularly set forth in the appended claims.

In the drawings:

Fig. 1 is an elevation of the improved cop holder;

Fig. 2 is an elevation of the base thereof;

Fig. 3 is an elevation of the outer sleeve;

Fig. 4 is a section on the line 4—4 of Figure 3;

Fig. 5 is a central section of the assembled base;

Fig. 6 is a view showing the parts thereof prior to assembly;

Fig. 7 is a section on the line 7—7 of Figure 5; and

Fig. 8 is a bottom plan view of the ratchet head.

It has been found desirable in the construction of metal cop holders, to mechanically lock the central tube thereof to a metal ratchet head so as to prevent relative turning, and to secure an outer sleeve to the central tube which has increased resilience and exerts a greater resistance to slipping of the yarn cop thereon.

I have therefore provided a cast metal ratchet head with a central opening having an annular upstanding hub, said hub having spaced slots or recesses therein; and I have positioned a central tube having an annular flange provided with spaced lateral displaced portions which form radial keys, in the ratchet head opening so as to seat the radial keys in the spaced slots or recesses of the hub,

the end of the tube passing through the ratchet head opening and being turned over the edge thereof to lock the parts together. On the central tube is welded an outer sleeve having two cylindrical end sections which embrace the tube, and an intermediate section formed of spaced resilient strips integral with the end sections and in arched relation to the central tube, each strip being laterally displaced in the same direction so that the frictional resistance to turning tends to shift the strips back and thus increases the engaging force; and following herewith is a detailed description of a specific cop holder embodying the structural and other features of my invention.

Referring to the drawings, the ratchet head 10 is preferably of cast metal, and has the usual ratchet teeth 11 thereon; a central circular opening 12 is provided, and an upstanding hub 13 surrounds the opening and has spaced slots or recesses 14 in the upper end thereof.

A central tube 15, preferably formed of sheet metal, has an annular flange 16 formed adjacent the lower edge thereof, as by upsetting, this flange having laterally displaced portions 17 on the lower edge thereof which serve as radial keys adapted to seat within the corresponding recesses 14 of the hub. In assembling the tube and the ratchet head, the lower end of the tube is passed through the central opening 12, the keys 17 seating within the recesses 14, and the end 18 is then turned over the lower edge of the central opening, as shown in Figure 7, to lock the two parts in assembled position.

Referring now to Figure 3, an outer sleeve 19 is provided, preferably of sheet metal, with two cylindrical end sections 20 and an intermediate section 21 having spaced strips 22, these strips being integral with the end sections and generally U-shaped in cross section with the rounded portions outward, each member being arched as shown in Figure 1, and then displaced laterally in a clockwise direction, as seen from the ratchet head. This displacement is therefore similar for each strip, and is in the direction of pull on the cop holder, thus tending to shift the dis-

placed parts back on increase of resistance; this shifting tends to increase the arching of the strips, and therefore increases the gripping force.

5 The outer sleeve is positioned on the central tube, and the end sections 20 are then welded or otherwise secured to the tube, the members 22 thereupon functioning as resilient cop holding members; the lateral displacement thereof increases the length of resilient cop engaging surface and resists slipping both on account of the arcuate engaging area and the tendency to increase the radial displacement of the strips upon excessive resistance to turning.

10 15 My improved cop holder is simple to construct and to assemble, has increased rigidity, increased holding power, and better resists slipping. While I have described a specific 20 construction embodying the features of my invention, it is obvious that desired changes in assembly or arrangement may be made to suit particular cop holder requirements, within the spirit and the scope of the invention 25 as defined in the appended claims.

I claim:

1. In a cop holder, a metal ratchet head 30 having a central opening, a central tube positioned in said opening, and a flange integral with said tube seated on one side of the opening, the end of the tube being turned over the edge of the other side of the opening.

35 2. In a cop holder, a metal ratchet head having a central opening, a hub around said opening, a central tube positioned in said opening, an integral flange thereon seated on the hub at one side of the opening, the end 40 of the tube being turned over the edge of the other side of the opening, and cooperating locking means on said flange and hub for preventing relative rotation thereof.

45 3. In a cop holder, a metal ratchet head having a central opening, a hub around said opening, said flange having spaced recesses therein, a central tube positioned in said opening, an integral flange thereon, and spaced displaced portions on said flange adapted to seat in said spaced recesses, the end of the 50 tube being turned over the edge of the other side of the opening to lock the parts together.

55 4. In a cop holder, a ratchet base, a central tube secured thereto, an outer sleeve secured to said central tube, and spaced longitudinally disposed resilient strips on said outer sleeve in arched relation to said central tube, said strips having portions displaced circumferentially with respect to the 60 tube.

5. In a cop holder, a ratchet base, a central tube secured thereto, an outer sleeve secured to said central tube, and spaced longitudinally disposed resilient strips on said 65 outer sleeve in arched relation to said cen-

tral tube, said members being substantially U-shaped in transverse cross section with the rounded base extending outwardly.

6. An outer sleeve for a cop holder or the like comprising cylindrical end portions, 70 spaced U-shaped connecting strips integral therewith, said strips being arcuately displaced both axially and circumferentially.

In testimony whereof I affix my signature.

FRANK MOSSBERG.
